UNITED STATES PATENT OFFICE

OTTO W. GITHENS, OF INDIANAPOLIS, INDIANA, ASSIGNOR TO UNIVERSAL CAMERA CORPORATION, OF NEW YORK, N. Y., A CORPORATION OF NEW YORK

DESIGN FOR A CAMERA

Application filed February 23, 1933. Serial No. 47,304. Term of patent 7 years.

To all whom it may concern:

Be it known that I, OTTO W. GITHENS, a citizen of the United States, residing at Indianapolis, in the county of Marion, State of Indiana, have invented a new, original, and ornamental Design for a Camera, of which the following is the specification, reference being had to the accompanying drawing, forming part thereof.

In the drawing, Fig. 1 is a side elevation,

Fig. 2 is a top plan view, and Fig. 3 is a front elevation of a camera showing my new design.

The camera always appears in the relative positions as shown on the drawing.

I claim:

The ornamental design for a camera, as shown and described.

OTTO W. GITHENS.
